UNITED STATES PATENT OFFICE.

AIMIE M. BAKER, OF CHICAGO, ILLINOIS.

SAVINGS-BANK.

1,271,416.

Specification of Letters Patent.

Patented July 2, 1918.

Application filed January 18, 1918. Serial No. 212,499.

To all whom it may concern:

Be it known that I, AIMIE M. BAKER, a citizen of the United States, residing at Chicago, in the county of Cook and State 6 of Illinois, have invented certain new and useful Improvements in Savings-Banks, of which the following is a specification.

This invention relates to the class of savings banks that are more especially intended 10 to receive and hold coins of different denominations; and has for its principal object to provide a device in which the coin slots are yieldingly guarded to permit of the free insertion of coins but automatically obstructed against the return of the same.

With this and other objects in view, reference is had to the drawings, in which—

Figure 1 is an elevation of a device embodying the improved features.

20 Fig. 2 is a vertical longitudinal section on line 2, Fig. 1.

Fig. 3 is a detached detail of construction.

Fig. 4 is a horizontal section on line 4, Fig. 2.

25 Fig. 5 is a broken away detail of the lower end of the receptacle showing a part of the locking feature, in perspective.

Fig. 6 is a detached plan of the removable bottom.

30 The savings bank receptacle A is of sheet metal and has a contour corresponding to that of an elongated cannon projectile having a conical pointed end B, and is provided with a coin slot 7. A bracket C is secured 35 to the insideside of the receptacle and is provided with a coin slot 8 registering in alinement with the slot 7, as best shown in Fig. 2. The bracket C is curved to correspond to the cylindrical wall of the receptacle and 40 sets up close thereto and is provided with a drop lug 9 perforated for the insertion of the fastening rivets 10 in retaining the same in place.

A number of balls 11 are loosely inserted 45 in the chamber 12 formed in bracket C, and positioned normally to close the coin slots, as shown in Fig. 2. A curved piece of rod or bar 13 is placed in the bottom of chamber 12 and provides a seat for the balls yieldingly guarding the coin slots. The diameter of the balls is greater than the width of the coin slots and they are so located that the entering edge of a coin or other object will contact with the balls below the center line 55 and raise the same up into the space 14 of chamber 12 and uncover the coin slots and

afford free entrance to the receptacle. When the pressure on the guard balls is relaxed they will gravitate to their closing position. The curved rod element 13 is held loosely in 60 place and when the bank receptacle is inverted and stood on its pointed end, the rod will follow the movement of the balls as they drop into space 14 and in turn close the coin-slots against the removal of any of 65 the bank contents.

The device is provided with means whereby the contents of the bank receptacle may be properly and conveniently removed at 70 any time.

The receptacle is provided with a removable bottom 15 having a reinforcing bottom rim edge 16 and an annular vertical flange 17 which telescopes over the lower end of the receptacle when in its closed relation, as shown in Figs. 1 and 2. The inside bottom is provided with a raised platform 18 which supports a lock casing 19 inclosing suitable lock mechanism not shown. When the bottom is in its locked position, the bolt 20 engages a socket 21 formed in the wall of the receptacle. The bottom flange 17 is provided interiorly with a number of studs 22 which are adapted to engage the angle slots 23 formed in the lower end of the receptacle, as shown in Fig. 5. When the bottom is to be placed in its closing position it should be held so that the studs 22 will enter the vertical part of slots 23 and then turn the bottom so that the studs will engage the horizontal angle of the locking slots. The bolt 20 is then thrown into its locking position (Fig. 2) by a proper manipulation of the key 24.

It will be noted that the bracket being angular in cross section and being curved braces the thin metal shell, at the point where it needs bracing, and prevents deformation of the walls of slot 7, by the insertion of an instrument therethrough. Even 100 though a blade be used to deform the slot 7 it could not be used effectively to bend the walls of slot 7, because of the shape of the bracket.

The balls 11 in order to rotate freely are 105 slightly spaced apart, and if there were two series of balls, in place of one series and the bar 13, the upper series would be liable to become alternately arranged with relation to the lower series, and they would drop 110 down too far, making these upper balls somewhat obstructive to the entrance of a

coin. The bar 13 however prevents the undue depression of the balls 11 and supports the balls so that they can be plainly seen through the slot,—the bar guiding the coin 5 so that it will exert its wedging action on the balls. Because the balls show through the slot, the bank has the effect of an explosive shrapnel shell, which has been cut away at one point to show the shrapnel.

10 What I claim and desire to secure by Letters Patent is—

1. A coin receptacle of thin metal simulating an explosive shell, the wall of the shell having a coin slot, disposed in a plane 15 at right angles to the longitudinal axis of the shell, means for guarding the slot comprising a plurality of freely movable balls supported behind the slot, and observable therethrough, a rod on which the balls normally rest by gravity, said rod being supported normally in a position behind the lower wall of the slot, and means for sup-

porting the rod and balls, preventing lateral movement of the balls and rod, but permitting limited vertical movement.

25

2. A coin receptacle of thin metal and having a base, and a coin slot parallel to the base, and means for guarding the coin slot, comprising a bracket attached to the wall and formed to provide a channel longer than 30 the slot, wider than the slot, and closed at its ends, there being a slot in the channel behind the coin slot, a rod loosely disposed in the channel and a plurality of loose balls in the channel, normally in contact with the 35 rod, the rod being normally just below the coin slot, with the balls resting by gravity thereon.

In testimony whereof I affix my signature in the presence of two witnesses.

AIMIE M. BAKER.
